SPARK-GAP.

1,162,659.

Specification of Letters Patent. Patented Nov. 30, 1915.

Application filed November 30, 1914. Serial No. 874,639.

To all whom it may concern:

Be it known that I, JAMES E. SEELEY, a citizen of the United States, residing at Los Angeles, in the county of Los Angeles, State of California, have invented new and useful Improvements in Spark-Gaps, of which the following is a specification.

This invention relates to a spark gap apparatus for high tension electrical machines and the like; and the primary object is the provision of a simple and compact apparatus which will operate over long periods without overheating and which will not deteriorate by continued use.

In spark gaps carrying a large current, such as is required in a heavy duty high tension machine, unless there is special provision made against overheating the spark gap apparatus will become excessively hot; and the metal of the terminal pieces will become so heated that arcing may melt the metal and destroy the terminals.

It is one of the objects of my invention to overcome these difficulties by providing a spark gap mechanism in which the discharge surfaces are kept in accurate parallelism with each other to evenly distribute the discharge over the surfaces; in which the discharge surfaces are long and narrow so as to allow ready access of air between the surfaces within the gap to keep the air in the gap as cool as possible; and in which there is sufficient means for radiating the heat from the terminal pieces. As a result of these features, my spark gap mechanism may be worked at its maximum capacity for a long period without becoming so heated that the finger cannot be placed upon it; whereas the ordinary spark gap apparatus becomes excessively hot if operated for any length of time. I make a practice of placing my spark gap apparatus on the inside of the box or casing which contains my high tension electrical apparatus; the spark gap working so cool that it is possible to place it within the box without any detrimental effects.

In the accompanying drawings I have shown a preferred form of my invention, in which drawings—

Figure 1 is a plan showing my complete spark gap apparatus, Fig. 2 is an elevation of the same, and Fig. 3 is an elevation taken as indicated by line 3—3 of Fig. 1.

In the drawings the numeral 10 may des-

ignate a case or box within which the spark gap may be placed; and 11 designates the base on which the apparatus is mounted. The apparatus embodies essentially a pair of terminals 12 preferably duplicates; one 60 of which is supported on a rigid support 13 and the other of which is supported upon a spring support 14. This spring support 14 is of such nature as to allow movement of the one terminal back and forth toward the 65 other terminal, in the direction indicated in Figs. 1 and 2. The springs, as hereinafter described, normally press the one terminal toward the other terminal; and the terminals are separated by manipulation of a 70 small hand wheel 15 on the outside of the case. This hand wheel 15 connects with a sleeve 16 internally screw threaded and engaging the screw threaded bolt 17, which bolt is attached directly to the terminal supported by the spring support 14.

The spring support is preferably constructed as illustrated in Figs. 1 and 3; embodying two parallel flat springs 20 secured to the base 11 at one end and carrying the 80 terminal bracket 21 at their other ends. Preferably, these springs 20 may be formed of a single piece of suitable metal bent into the hollow rectangular shape illustrated, the long sides of the rectangle forming the 85 springs. The springs are then easily affixed to the base by means of a clamp bar 22, and the terminal bracket 21 is easily affixed to the springs by means of another clamp bar 23. Preferably, the two terminals 12 90 are duplicates, and each embodies a pair of clamp bars 25, radiating sheets 26 clamped between the bars, and a contact bar 27 mounted in the face of one of the clamp bars 25. The clamp bars 25 are preferably semi-cylindrical, their cylindrical faces being adjacent each other; and the radiating sheets 26 are clamped between the cylindrical faces of these bars; the radiating sheets spreading out in fan configuration on each side as illustrated in Fig. 1. These radiating sheets may be constructed or formed in any desired manner; but may preferably be formed each of a single continuous strip of sheet metal, such as copper, bent back and forth a number of times and clamped tightly between the clamping bars 25. Each of the terminals has a bolt 30, the bolt 17 being a continuation of one of the bolts 30. These bolts are secured in one of the clamp bars 105 110

25 and pass through the heat radiating sheets 26 and through the other bar and then through the support 13 or the bracket 21; a nut 31 serving to draw all the parts tightly 5 together and clamp the heat radiating sheets tightly and solidly between the clamping bars. The heat radiating sheets are preferably of copper and the clamping bars are preferably of brass. The construction is 10 such that heat generated at the gap is very readily conducted through the bars 25 to the radiating sheets 26 and radiated by them to the surrounding atmosphere.

The bars 25 have a long contact with the 15 sheets 26; and there is a very large section of metal for the conduction of heat directly from the contact bars 27 to the radiating sheets 26. This feature of the elongate clamp bars having a long contact with the radiating sheets is an important one. The path traveled by heat from the contact bar to the radiating sheets is short. The clamp bar being 20 of solid metal, being in close contact with the radiating sheets, the radiating sheets being 25 in close contact where they are clamped together, and the contact between the clamp bar and the radiating sheets, and between the radiating sheets themselves, being long —all these features cause the ready and wide 30 distribution of heat over all the radiating surface. It will be noted that the radiating sheets are so placed that an upward draft of air is induced by heating the air between and around them.

35 The contact bars 27 are preferably made of silver; and their opposing contact faces are carefully dressed to be accurately parallel to each other. Once the apparatus is set up and these contact faces properly 40 dressed the contact faces will always be maintained parallel to each other by the parallel action of the spring support 14. Being maintained in parallelism, the discharge across the gap is evenly distributed over 45 the contact surfaces and has no tendency to concentrate at any particular point. This fact, together with the fact that the generated heat is quickly carried away, and also that the contact faces are long and narrow 50 allowing a comparatively free circulation of air in the gap, is conducive to indefinite life of the contact pieces. There is no tendency to overheat the metal of the contact pieces and there is no tendency to heat the 55 contact pieces any more at one point than at another. The temperature of the whole apparatus is kept low at all times; and the total result is that my spark gap apparatus with reasonable care, has an indefinite life 60 even when used for long periods with very heavy currents.

Having described my invention, I claim:

1. A spark gap apparatus, comprising two 65 duplicate terminals mounted to be relatively movable to and from each other, each em-

bodying a pair of longitudinal clamp bars, heat radiating sheets clamped between the bars, and a thin contact bar carried by one of said clamp bars, the contact bars of the two members opposing each other edgewise. 70

2. In a spark gap apparatus, a terminal embodying a pair of parallel metal clamp bars, heat radiating sheets clamped between the bars, and an elongate contact bar mounted upon one of the clamp bars presenting 75 a thin elongate edge away from the clamp bar.

3. In a spark gap apparatus, a terminal embodying a pair of parallel semi-cylindrical metal clamp bars placed with their flat 80 faces outwardly, heat radiating sheets clamped tightly between the bars and spreading out in fan configuration on each side, and an elongate contact bar set in the flat face of one of the clamp bars presenting a 85 thin elongate edge away from the clamp bar.

4. A spark gap apparatus, comprising two duplicate terminals arranged opposing each other, each terminal embodying a pair of parallel metal clamp bars, heat radiating 90 sheets clamped between the bars, and an elongate contact bar mounted upon one of the clamp bars presenting a thin elongate edge away from the clamp bar, against the contact bar of the other terminal, and means 95 for supporting said terminal so that one may be moved to and from the other keeping the contact bars parallel with each other.

5. A spark gap apparatus, comprising two 100 duplicate terminals arranged opposing each other, each terminal embodying a pair of semi-cylindrical metal clamp bars placed with their flat faces outwardly away from each other, heat radiating sheets clamped tightly between the bars and spreading out 105 in fan configuration on each side, and an elongate contact bar set in the flat face of one of the clamp bars presenting a thin contact edge away from the clamp bar toward the contact bar of the other terminal, and means 110 for supporting said terminals so that one may be moved to and from the other keeping the contact face of the contact bars parallel to each other.

6. A spark gap apparatus, comprising two 115 duplicate terminals arranged opposing each other, each terminal embodying a pair of semi-cylindrical metal clamp bars placed with their flat faces outwardly away from each other, heat radiating sheets clamped 120 tightly between the bars and spreading out in fan configuration on each side, and an elongate contact bar set in the flat face of one of the clamp bars presenting a thin contact edge away from the clamp bar toward 125 the contact bar of the other terminal, a rigid support for one of the terminals, and a spring support for the other terminal embodying a pair of spaced parallel flat springs. 130

7. In a spark gap apparatus, a base, a rigid support thereon, a terminal on said rigid support, a spring support and a terminal thereon opposing the first mentioned terminal, said spring support embodying a pair of spaced parallel flat springs of equal length having one end secured to the base and the other end supporting the terminal.

In witness that I claim the foregoing I have hereunto subscribed my name this 10th 19 day of November 1914.

J. E. SEELEY.
